UNITED STATES PATENT OFFICE

150,989

DESIGN FOR A FOOD CHOPPER AND GRINDER

Herbert J. Kline, Jackson, Mich., assignor, by
mesne assignments, to National Die Casting
Company, Chicago, Ill., a corporation of Illinois

Application June 28, 1946, Serial No. 131,128

Term of patent 14 years

(Cl. D89—1)

To all whom it may concern:

Be it known that I, Herbert J. Kline, a citizen of the United States, residing at Jackson, in the county of Jackson and State of Michigan, have invented a new, original, and ornamental Design for Food Choppers and Grinders, of which the following is a specification, reference being had to the accompanying drawing, forming part thereof.

In the drawing,

Fig. I is a top view of the food chopper and grinder, showing my new design,
Fig. II is a side elevational view,

Fig. III is a view taken from the handle end, and

Fig. IV is a view taken from the discharge end.
I claim:

The ornamental design for a food chopper and grinder, as shown.

HERBERT J. KLINE.
